UNITED STATES PATENT OFFICE.

JOSEPH F. HORNE, OF REVERE, MASSACHUSETTS.

NECKTIE AND THE METHOD OF MAKING UP SAME.

Application filed August 20, 1921. Serial No. 493,792.

To all whom it may concern:

Be it known that I, JOSEPH F. HORNE, a citizen of the United States of America, residing at Revere, in the county of Suffolk and State of Massachusetts, have invented a new and useful Necktie and the Method of Making Up Same, of which the following is a specification, reference being had to the accompanying sheet of drawing.

10 My invention relates more particularly to neckties of the so-called four-in-hand types and has for its object to provide a tie and a method of making up the same to yield a ready-to-wear necktie having a permanent knot, an adjustable collar fitting loop, and a disengaging tie lock, all of which will be hereinafter more fully explained.

Other objects and advantages of the invention will be gathered from the description following herein and considered in connection with the accompanying drawing wherein the invention is shown embodied.

The terms employed herein are used in the generic and descriptive sense to designate the elements illustrated, and are therefore not primarily intended as terms of limitation.

In order to illustrate my invention, I have shown in the accompanying drawing an embodiment thereof but without being specifically limited thereto wherein:

30 Fig. 1 represents a view showing my tie made up and ready for use;

Fig. 1^a represents a rear view of the front flap of the tie shown in Figure 1;

35 Fig. 2 represents a sectional view taken substantially on line 2—2 on Figure 1;

Fig. 3 represents a view of the tie previous to being knotted and made up;

Fig. 4 represents a similar view to Figure 3 but shows a modification therein;

40 Fig. 5 represents a sectional view taken on line 5—5 on Figure 1;

Fig. 6 represents a rear view of the tie-lock or anchoring section of the tie;

45 Fig. 7 represents a sectional view taken on line 7—7 on Figure 6;

Fig. 8 represents a sectional view taken on line 8—8 on Figure 3;

50 Figs. 9 to 12 inclusive represent the different successive stages which are embodied in

the within method for making up the tie shown and disclosed herein.

Like reference characters refer to like parts throughout the several views of the drawing.

The letter T represents my type of tie in its entirety and which comprises the front flap F, the knot section K, the neck-band section N, the rear flap R, the pocket P, and the anchor end A.

B represents the back of the front flap of the tie which is preferably folded over as Figure 1^a indicates and seamed together at S to make the tie tubular at that section. The pocket P is provided in the seamed section of the tie as indicated in Figures 1^a and 6, and may be formed in the seam S as the opening P shown in the drawing.

It may be here noted that the within tie resembles the ordinary and usual four-in-hand ties but differs therefrom in the respect that the front flap is provided with the back pocket P and the rear flap is provided with the anchor end A as aforesaid. Therefore the usual and customary designs and methods of manufacturing the present types of four-in-hand ties may be generally followed in the construction of the within tie, adding however the features just mentioned thereto to yield the additional features embodied and required in the within invention.

Having thus described the within tie in detail the method of making up the same to form a ready-to-wear knotted and adjustable four-in-hand tie is as follows:

The front flap at the knot section K is wound around the rear flap R as shown in Fig. 9 to completely encircle the latter thus forming a loop through which the rear flap R may slide. Said loop may be made sufficiently tight to crush and grip the flap R therein, requiring thus an appreciable pull thereon to permit the same to be drawn there-in against the friction existing thereagainst. Then the knot section K is loosely wound twice around said loop over the spacer element as the finger H as shown in Figs. 10 and 11 and finally the front flap F is drawn through the space provided by the finger H

which is now withdrawn as shown in Fig. 12 and the knot K is tightened up and shaped as shown in Fig. 1.

The tie thus takes on the appearance of an ordinary made up four-in-hand tie but provides for a permanent knot which is not disturbed neither in putting the tie on the collar nor while being removed therefrom. The neck section N when the tie is made up as just explained provides for an adjustable loop L which is adjustably increased or decreased by drawing the rear flap through the knot in one direction or the other according as may be desired. The knot thus forms a noose through which the rear flap may be drawn; it being understood that the anchor end A which may be provided with a stiffening piece as indicated in Fig. 8, will as shown in Fig. 1 by the dotted position "a," prevent the flap R from being completely withdrawn through the knot K.

The tie is accordingly designed to provide an adjustable neck loop L which is slipped over the head of the wearer, the neck section N is then associated with the collar and finally the flap R is drawn through the knot K to contract the loop L to engage the neck section N snugly with the collar, bringing up and positioning the knot K in proper relationship with the collar.

With the tie thus tightly set with the collar the anchoring end A is then inserted in the pocket P provided therefor and drawn down in the tubular section as shown in Fig. 6 to set the exposed section of the flap R flat and adjacent with the back of the front flap F of the tie.

The engagement of the rear flap with the pocket P of the front flap will securely hold the two flaps together and will prevent the tie from loosening about the collar with which the same is being worn.

It will thus be here noted that the anchor end A cannot become disengaged from the pocket by reason of the peculiar connection there-between unless deliberately separated therefrom by the wearer, thus assuring a locking means for holding the tie set as long as the wearer requires it to stay set. On the other hand when the anchor end is disengaged from the pocket, the tie is readily loosened from the collar to permit the removal thereof from the collar.

As may be understood the knot of the tie is not disturbed and when once made up may be worn over and over without showing wear. The tie when worn cannot be told from the regular and customary four-in-hand ties; the knot is hand made and is identical with the hand made four-in-hand ties which require the knots to be made up each time that they are worn.

The within tie thus provides a ready-to-wear knotted and adjustable tie which may fit any size or type of collar, is easier to ap-

ply to and to be disengaged from the collar, preserves the life of the tie, is free from wrinkles, always looks neat and well formed, and finally it stays firmly set with the collar when adjusted thereto.

It is a known fact that in the case of the ordinary four-in-hand tie the constant tying and untying of the knot wrinkles and cracks the material and the life of the tie is thereby greatly shortened, then again not all people are adapted to making up neat tie knots, very few people can make up the knot in the tie a second time at the same place which it originally assumed, and finally much time is lost in making and unmaking the knot. All of the above objections are eliminated in the within described and disclosed tie. The expense of manufacturing my type of tie is no greater than the ordinary tie on the market and which does not provide the advantages nor the features embodied in my type of tie.

While the preferred embodiments of my invention have been described in detail, it will be understood that I do not wish to be limited to the particular construction set forth, since various changes in the form, design, and construction may be resorted to without departing from the spirit and scope of the invention, or destroying any of the advantages contained in the same, heretofore described and defined in the subjoined claims.

Having thus described my invention in detail, what I claim as new is:

1. A four-in-hand necktie comprising a tubular front flap having an opening in the back thereof and a rear flap having an enlarged portion at the end thereof and adapted to be inserted within the tubular front flap through the said opening to thereby releasably hold the front and rear flaps in juxtaposition.

2. A four-in-hand necktie comprising a front flap having a pocket section in the back thereof and a rear flap having an enlarged portion at the end thereof adapted to fit into the pocket section to releasably hold the front and rear flaps in juxtaposition and to prevent the rear flap from being withdrawn through the noose in the knot of the tie.

3. A four-in-hand necktie comprising a front flap provided with a pocket section in the rear thereof; a knot section; a neck section; and a rear draw flap provided with an enlarged anchoring end adapted normally to engage with the pocket of the front flap for securing the flaps of the tie together to hold the tie set in the wearing position and otherwise to prevent the rear draw flap of the tie from being withdrawn from the knot of the tie when made up therein.

4. The method of making up a four-in-hand tie with a knot and an adjustable neck

loop comprising the following steps, winding the front flap around the rear flap to completely encircle the same forming a noose in the knot of the tie through which the 5 rear flap may be frictionally drawn; then loosely winding the front flap over the noose formed in the aforesaid step to form two additional coils thereto; then, passing the front flap through the neck loop of the tie

and drawing the same between the noose 10 formed in the first step and the coils in the second step; and finally tightening up and shaping the knot.

In testimony whereof, I hereunto set my hand this 18th day of August, 1921.

JOSEPH F. HORNE.

Witness:

DAVID LICHTENSTEIN.
